SOCKET HEAD SCREW

Dominic V. Stellin, Bronx, N. Y.

Application June 16, 1944, Serial No. 540,621

7 Claims. (Cl. 85—45)

The present invention pertains to screws of the type having a recess or socket in the head to receive a screw driver, known as the internal wrenching type.

In the use of such screws of existing forms, especially in the case of flat head screws, the head has been known to break off under the action of the power driven screw driver. The head flies off with such force as to injure the operator, if it strikes him, as well as nearby workers crowded together on modern assembly lines. In addition the work is scratched or defaced and the screw head is burried, so that considerable time is lost in removing the broken screw.

One of the objects of the invention is to eliminate the breaking of screws and the resulting injury and damage. The hexagon type of socket, for example, is very popular but is seldom used in flat head screws due to the fact that the thickness of metal around the socket becomes thinner and weaker as the head tapers inwardly of the screw axis. According to my invention, the socket also is tapered inwardly, in various forms as well as the hexagonal, so that the metal thickness around the socket remains constant and the liability of breakage is practically eliminated.

Another difficulty with the present socket head screws is that the power screw driver does not readily enter the socket, since there must be accurate registration of non-circular shapes. Another object of the invention is to overcome this difficulty and is accomplished also by the tapering socket in conjunction with a tapering screw driver. Thus, the screw driver enters the socket quite freely and is gradually seated or registered after entering, thereby avoiding the burring of the screw head top and damaging of the work resulting from initial misalignment.

Still another object of the invention is to eliminate breaking of sharp corners on the screw driver and within the socket. For example, a finger-shaped recess presents sharp corners extending into the recess and liable to breakage. According to the invention, breakage is avoided by rounding off such corners. Again, a triangular recess requires sharp corners on the tool, and this situation is met by rounding the angles of the triangle and also rounding the edges of the screw driver. With the same object in view, sockets with large internal angles are contemplated, since the corresponding large angles of the screw driver strengthen the sharp corners and protect them from breakage.

The invention is fully disclosed by way of exam-

ple in the following description and in the accompanying drawings in which:

Figure 1 is a plan view of a flat head machine screw;

5 Figure 2 is a plan view of a machine set screw;

Figure 3 is a plan view of another machine set screw;

Figures 4, 5 and 6 are longitudinal sections of the screws shown respectively in Figures 1, 2 and 3;

10 Figure 7 is a plan view of a set screw;

Figure 8 is a plan view of another flat head machine screw;

Figure 9 is a plan view of still another flat head machine screw;

Figures 10, 11 and 12 are longitudinal sections of the screws shown respectively in Figures 7, 8 and 9;

15 Figure 13 is a plan view of a filister type screw;

Figure 14 is a plan view of another set screw;

Figure 15 is a plan view of a round head machine screw;

Figures 16, 17 and 18 are longitudinal sections of the screws shown respectively in Figures 13, 14 and 15;

20 Figure 19 is a plan view of a stripper screw;

Figure 20 is a plan view of a wood screw;

Figures 21 and 22 are longitudinal sections of the screws shown respectively in Figures 19 and 20;

25 Figure 23 is an elevation of a wrench for a socket head cap screw;

Figure 24 is an elevation of a machine wrench for a socket head screw;

30 Figure 25 is a longitudinal section of a socket head cap screw with a different shape of socket; and

Figure 26 is a plan view thereof.

Reference to these views will now be made by use of like characters which are employed to designate corresponding parts throughout.

In Figures 1 and 4 is shown a flat head machine screw including a shank 1 and a downwardly tapered head 2. The threads, not shown, are conventional. In the head is formed a recess

45 3 which, in this case, is hexagonal in cross section. Approximately the upper third of the height of the recess is of uniform dimensions as indicated at 4, while the remainder converges

50 downwardly at 5, at an angle of 10 to 15 degrees to the projected wall 4. The upper or outer edge of the recess is preferably bevelled slightly at 6 or turned on a radius.

55 This construction is similar in its general properties to the modifications described hereinafter.

The screw driving tool is shaped to fit in the socket or recess 3 and, being smaller at the entering end, is easily received in the wider end of the socket. Due to the taper of both the tool and the socket, the tool seats gradually, without undue clashing of surfaces and burring of the screw. Also, the provision of a tapering socket in a tapering screw head maintains a substantially uniform wall thickness and strength in the head. In contradistinction a socket of uniform cross sectional area in a tapering head weakens the head at the bottom of the socket, resulting in breakage of the screw, injury to adjacent workers, damaging of the work and nearby equipment, and loss of time in removing the broken screw, as previously set forth.

The entry of the driving tool is further facilitated by the obtuse internal angles of the hexahedral socket. Where these angles are acute, as in modifications presently to be described, the corners are rounded to eliminate breaking of corresponding tool angles or protruding angles in the socket.

Figures 2 and 5 show a machine set screw having a threaded shank 10 of uniform diameter. The socket 11 therein is triangular in plan section with approximately the upper third of its length being of uniform cross sectional area, at 12, and the remainder tapering slightly inward at 13. A chamfer 14 is formed at the upper edge of the socket, and all angles are rounded at 15. Thus, the corresponding angles of the driving tool need not be sharp and breakable.

In the machine set screw 20 shown in Figures 3 and 6, the socket 21 is of a substantially four-leaf clover design. The upper portion 22 tapers inwardly while the lower 25%, approximately, of its length is straight-walled at 23. The upper edge of the socket is chamfered at 24. Such a design necessarily presents inwardly converging angles or internal angles exceeding 180°. The apices of such angles would ordinarily be liable to breakage under impact and pressure of the driving tool. In order to eliminate this possibility, the angles are rounded at 25 both in the socket proper and in the chamfer.

Figures 7 and 10 show a set screw 30 having a socket 31 with four sides 32 that are convex within the socket. The upper portion of the socket tapers inwardly at 33, and the bottom fraction is straight-walled at 34. The corners formed between adjacent sides 32 are rounded at 35 in order not to require a sharp-cornered driving tool as previously set forth.

In Figures 8 and 11 is shown a flat head machine screw having a shank 40 and a tapered head 41. The socket 42 therein has two parallel edges 43, in any transverse plane, joined by two curved sides 44 concave within the socket. It is evident that this arrangement of flat and curved walls eliminates sharp corners between adjacent walls. The height of the socket is divided substantially into thirds, the upper third being of uniform cross sectional area at 45, the middle third tapering inwardly at 46, and the lower third being also of uniform cross section at 47. The upper edge is chamfered at 48.

A similar stepped formation is provided in the flat head machine screw shown in Figures 9 and 12, having a shank 50 and a head 51. The cross sectional configuration of the socket 52 is substantially square, with the internal corners rounded at 53. The upper edge is chamfered at 54. The upper portion of the socket is of uniform cross section at 55, the middle portion 56

tapered inwardly, and the bottom portion 57 again of uniform cross section.

Figures 13 and 16 show the invention applied to a filister type screw having a threaded shank 60 and a shouldered head 61. The socket 62 is hexahedral and tapers inwardly along substantially its entire length except for a considerable chamfer 63 at its upper end. As in Figures 1 and 4, the internal angles are obtuse, requiring similar angles on the driving tool. These angles, although converging to sharp apices, are hardly liable to breakage, because of their obtuse character.

Figures 14 and 17 illustrate a set screw 70 having a cross shaped socket 71 that tapers inwardly and has its upper end chamfered at 72. As in Figures 3 and 6, some of the internal angles are greater than 180° and present edges projecting into the socket. Such edges are rounded off as indicated by the numeral 73.

In Figures 15 and 18 is shown a round head set screw having a threaded shank 75 and a head 76. The socket 77 therein is of three-fingered formation and presents obtuse internal angles within the socket. These are rounded off at 78 for the reasons previously set forth. The socket tapers inwardly along nearly its entire length and has a substantial chamfer 79 at its upper end.

Figures 19 and 21 show a stripper screw having a shank 80, a threaded end 81 and a cylindrical head 82. The socket 83 therein is multi-fingered and presents internal obtuse angles which are rounded off at 84 as previously set forth. The socket tapers inwardly and has its upper end chamfered at 85.

In Figures 20 and 22 is shown a wood screw having a threaded shank 90 and a tapered head 91. The socket 92 is also multi-fingered, and the obtuse internal angles formed thereby are rounded off at 94. The socket tapers inwardly and is formed with a chamfer 95 at its upper end.

A typical machine-operated driver for the screws is shown in Figure 23. It consists of a shank 96 carrying a head 97 shaped to fit in the socket of the particular screw to be driven. The head tapers at 98 and is otherwise shaped to conform to the socket.

In Figure 24 is shown a hand wrench for a screw having a socket of the finger type. The shank 99 is preferably at a right angle to the head 100. The head tapers at 101 to conform to the socket and embodies rounded lugs 102 shaped to fit in the aforementioned rounded corners of the socket.

The taper angles of the sockets, although stated in one case to be between 5 and 10 degrees, may be smaller or larger according to particular requirements. The various shapes of sockets are not limited in their application to the specific types of screws or heads in which they are shown. Any disclosed socket shape is applicable to any type of screw or head, whether or not illustrated herein.

In Figures 25 and 26 is shown a socket head cap screw 110 having a head 111 with a recess 112 therein. The recess is in the form of a two-blade propeller, having two convex side walls 113 and two shorter concave side walls 114. The corners formed by adjoining walls are rounded at 115 to accommodate a round-cornered driving tool as previously set forth.

The upper edge of the recess 112 is chamfered at 116, from which approximately half the depth of the recess is of uniform cross sectional configuration as shown at 117. The remaining, lower

portion of the recess tapers downwardly at 118.

The curved walls of the recess facilitate the engagement of the driving tool with the screw head in driving relation and similarly facilitate disengagement when similar action occurs in all the constructions having curved walls in whole or in part, convex or concave, or a combination thereof.

In all embodiments described herein, the primary purpose is to avoid breaking the screw head or the driver, especially when the screw has been driven home. This purpose is accomplished, for the most part, by the avoidance of sharp corners in the recesses and the provision of a round-cornered driving tool which rides out of the recess more readily than a sharp-cornered tool from a sharp cornered recess. Again, the provision of large internal angles, or the avoidance of deep radial pockets, in the recess contributes further to the easy seating of the driver and easy automatic withdrawal of the driver from the recess.

In the embodiments having a stepped recess with a straight-walled portion at the bottom, the screw driver makes its driving engagement comparatively quickly. This is for the reason that the driver need not seat fully in the recess before commencing to drive. It commences to drive as soon as it enters the straight-walled portion whether above or below, and then completes the seating movement. A uniformly tapered recess and driving tool on the other hand, do not establish driving relation until the tool has fully seated.

Although specific embodiments of the invention have been illustrated and described, it will be understood that various alterations in the details of construction may be made without departing from the scope of the invention as indicated by the appended claims.

What I claim is:

1. In a screw, a head formed with a recess having a plurality of symmetrically arranged faces, one end of said recess being of a uniform cross-sectional area and co-axial with the screw, and an adjacent portion of said recess tapering inwardly of the screw at an angle of about 5° to the screw axis, said tapering portion being truncated in a plane perpendicular to its axis.

2. In a screw, a head formed with a recess having a plurality of symmetrically arranged faces, the inner end of said recess being of a uniform

cross-sectional area and co-axial with the screw, and an adjacent portion of said recess tapering inwardly of the screw at an angle of about 5° to the screw axis.

3. In a screw, a head formed with a recess having a plurality of symmetrically arranged faces, the outer end of said recess being of a uniform cross-sectional area and co-axial with the screw, and an adjacent portion of said recess tapering inwardly of the screw at an angle of about 5° to the screw axis.

4. In a screw, a head formed with a recess having a plurality of symmetrically arranged faces, the end portions of said recess being each of uniform cross-sectional area and co-axial with the screw, the inner end portion being of smaller cross-sectional area than the outer portion, said recess having an intermediate portion with walls tapering from said outer portion to said inner portion.

5. In a screw, a head formed with a recess having a plurality of symmetrically arranged faces, the end portions of said recess being each of uniform cross-sectional area and co-axial with the screw, the inner end portion being of smaller cross-sectional area than the outer portion, said recess having an intermediate portion with walls tapering from said outer portion to said inner portion, the corners of said portions being rounded.

6. In a screw, a head formed with a recess having a plurality of symmetrically arranged faces, the end portions of said recess being each of uniform cross-sectional area and co-axial with the screw, the inner end portion being of smaller cross-sectional area than the outer portion, said recess having an intermediate portion with walls tapering from said outer portion to said inner portion, certain corresponding walls of each of said portions being curved and the remaining walls being plane.

7. In a screw, a head formed with a recess having a plurality of symmetrically arranged faces, the end portions of said recess being each of uniform cross-sectional area and co-axial with the screw, the inner end portion being of smaller cross-sectional area than the outer portion, said recess having an intermediate portion with walls tapering from said outer portion to said inner portion at an angle of about 5° to the screw axis.

DOMNICK V. STELLIN.
